(57) **CLAIM**

We claim the ornamental design for a pet feeder with non-skid lower surface, as shown and described.

DESCRIPTION

FIG. 1 is a perspective view of a pet feeder with non-skid lower surface showing our new design;

FIG. 2 is a front elevation view of the pet feeder with non-skid lower surface, the rear and sides being the same;

FIG. 3 is a top plan view thereof; and,

FIG. 4 is a bottom plan view thereof.

CERTIFICATE OF CORRECTION

PATENT NO. : Des. 565,253 S
APPLICATION NO. : 29/269226
DATED : March 25, 2008
INVENTOR(S) : Modi et al.

Page 1 of 4

It is certified that error appears in the above-identified patent and that said Letters Patent is hereby corrected as shown below:

Delete Title page illustrating a figure, and substitute therefor, new Title page illustrating a figure. (attached)

Delete drawing sheets 1-2, consisting of figures 1-4, and substitute therefor drawing sheets 1-2, consisting of Figures 1-4, as shown on the attached sheet.

Signed and Sealed this

Second Day of September, 2008

JON W. DUDAS
Director of the United States Patent and Trademark Office
